D. R. MACBAIN,
GAGE GLASS APPARATUS.
APPLICATION FILED DEC. 26, 1912.

1,105,150.

Patented July 28, 1914.

UNITED STATES PATENT OFFICE.

DONALD R. MACBAIN, OF CLEVELAND, OHIO.

GAGE-GLASS APPARATUS.

1,105,150.

Specification of Letters Patent. Patented July 28, 1914.

Application filed December 26, 1912. Serial No. 738,620

To all whom it may concern:

Be it known that I, DONALD R. MACBAIN, a citizen of the United States, residing at Cleveland, in the county of Cuyahoga and State of Ohio, have invented certain new and useful Improvements in Gage-Glass Apparatus, of which the following is a specification.

This invention has reference to the provision of an improved form of mechanism whereby to safe-guard the fireman from the danger of injury due to the bursting of the steam boiler gage glass, such for example as is commonly used in locomotive work.

The first of the objects of this present invention is the provision of a device which will insure an effective drainage or escape not only for the steam and hot water in case the glass bursts, but also for the broken particles of the glass itself, and this without interfering in any manner with the ready inspection of the glass or the height of the water therein.

The above as well as such other objects as may hereinafter appear, I attain by means of a construction which I have illustrated in preferred form in the accompanying drawings, wherein,—

Figure 1 represents in side elevation the rear end of a boiler shell with my improvement applied thereto; Fig. 2 is a vertical sectional view through the improved gage glass mechanism; Fig. 3 is a transverse sectional view on the line III—III of Figure 4; Fig. 4 is a rear view in elevation of the mechanism shown in Fig. 2; and Fig. 5 is a detailed view indicating the preferred form of connection which I employ between the casing of the device and the outlet pipe or drain tube.

Referring now more particularly to Figure 1, it will be seen that I have therein indicated the rear end of a boiler shell marked 6 on which there is a valve connection 7 leading to a tube 8 that in turn connects at its lower end with the upper end of a casing 9 which forms the main casing or body of my apparatus, and in which I provide a couple of sockets or seats indicated particularly in Fig. 3 at the point marked 10, such seats being constructed to receive the vertically slidable flat glass pieces or windows 11 which are to be made of heavy, durable glass such as will withstand considerable heat and shock. The plates or glass pieces

11 are held by the recesses at either side of the socket 10 and are free to be slid upwardly and removed for cleaning or for inspection of the gage glass on the interior of the main or body casing 9. The gage glass 60 proper—indicated at 12—is secured by means of the packing 13 at its upper and lower ends through the instrumentality of suitable glands or packing, nuts 14 and 15, the lower nut 15 being formed as the projection upon the body 16 of the valve 17 that controls the lower communication from the interior of the gage glass to the boiler.

Referring now more particularly to Fig. 4, it will be seen that in constructing the body portion of the apparatus, I have made the metal or intermediate part of considerable diameter or dimension, as indicated at 19 and provided the same with the neck portions 20 and 21 and with laterally extended and inclined back wall 22 which is so arranged that there is a full and free outlet 23 of ample size and of such direction as will most freely permit the ready escape of the steam and hot water and particles of 80 glass in case of a rupture of the tube 12. The windows or plates 11 are of substantial thickness to withstand the force of a rupture of the tube 12 and while they will permit some leakage of steam around their 85 edges, they are sufficiently tight to entirely prevent any injury to the attendant.

In order to secure the best results, I arrange the outlet nozzle or projection 24 which also is of ample size—so that it leads 90 in a sloping downward direction and is connected with the lower discharge tube 25 by means of a telescopic or sliding connecting member 26, and is readily secured in place by the cotter pin 27 when it is raised in position as shown. The outer tube or escape pipe 25 preferably leads to some point underneath the floor of the cab of the engine or somewhere at such distance from the attendant as will avoid danger of scalding or injury, and is preferably securely attached to the boiler head by means of supporting devices 28, and the telescopically movable member 26 affords a convenient means for connecting or disconnecting the body portion or 105 the device where such operation is necessary.

The operation of my invention will, it is thought, be quite clear in connection with the accompanying description of the structure, it being obvious that with the arrange- 110

ment of the parts as described, in case of any breakage of the glass tube 12, the steam and hot water which escapes together with the broken parts of glass will find a ready 5 outlet through the lateral chamber in front of the wall 22 and the large opening 23 and pipe 25; and in order to further safeguard against danger of breakage of the glass plates 11, I make the device with the chamber 10 around the tube 12 as well as the outlet passage described as of sufficient size so as to prevent the creation of any sudden or material pressure against the slides or plates 11, and with a view to the accomplishment 15 of the same object, I extend the chamber that surrounds the tube 12 for a considerable distance longitudinally along the tube so that no matter where the breakage occurs, there will be ample room for the escape 20 of the parts or pieces and the water and steam.

Having thus described my invention and illustrated its use, what I claim as new and desire to secure by Letters Patent, is the following:

1. In combination in gage glass apparatus, a gage glass, a casing surrounding the gage glass and provided with a window and a relief opening leading from one end of the 30 casing, the cross sectional area of the casing increasing from the end remote from the relief opening to the end having said opening.
2. In combination in gage glass apparatus, a gage glass, a casing surrounding the 35 gage glass and provided with a window and a relief opening leading from the lower end of the casing, the rear wall of the casing extending downward and inclined to the

rear providing an enlargement at the lower end of the casing.

3. In combination in gage glass apparatus, a gage glass, a casing surrounding the gage glass and provided with a window and with a longitudinally inclined rear wall lying opposite the gage glass, there being a relief 45 opening leading from the end of the casing having the larger cross sectional area.

4. In combination in gage glass apparatus, a gage glass, a casing surrounding the gage glass and provided with a window, the 50 said casing having its wall behind the gage glass bulged out from a pocket extending longitudinally of the casing from the upper to the lower portion thereof and providing a relief area, and a vertical pipe of relatively 55 large cross sectional area leading into the lower portion of said relief area, and in approximate alinement with the pocket the rear wall of the relief pocket lying farther from the gage glass than the inner surface 60 of the said window from said gage glass.

5. In combination in gage glass apparatus, a gage glass, a casing surrounding the gage glass and provided with a window, and with a tapering relief pocket having an inclined 65 wall back of the gage glass, and a relief pipe leading from the larger portion of the pocket.

In testimony whereof I have hereunto signed my name in the presence of the two 70 subscribed witnesses.

DONALD R. MACBAIN.
